UNITED STATES PATENT OFFICE.

RAYMOND McNELLEY, OF NORTHPORT, MAINE.

DESIGN FOR AN ASH-SPRINKLER.

SPECIFICATION forming part of Design No. 35,300, dated November 19, 1901.

Application filed September 24, 1901. Serial No. 76,405. Term of patent 7 years.

To all whom it may concern:

Be it known that I, RAYMOND McNELLEY, a citizen of the United States, residing at Northport, in the county of Waldo and State 5 of Maine, have invented and produced a new and original Design for Ash-Sprinklers, of which the following is a specification, reference being had to the accompanying drawing, forming part thereof.

10 In the drawing there is shown a perspective view of an ash-sprinkler embodying my new design.

As shown in the drawing, the leading or material feature of my design consists of the 15 hollow cylindrical portion 5, having radiating perforations 6, and at one end of which is the cap 7, so that the cylindrical portion is closed at one end. At the opposite end of the cylindrical portion from the cap is the slightly-en-

larged elbow 8, which is directed upwardly 20 and from which extends the upwardly-projecting cylindrical and hollow portion 9, the elbow being also hollow. At the upper end of the upright portion is the flared portion 10, at the edge of which is the hook-shaped finger 25 11, which lies above the portion 5.

Having described my invention, what I claim as new, and desire to secure by Letters Patent, is—

20 The design for an ash-sprinkler, as herein 30 shown and described.

In testimony whereof I affix my signature in presence of two witnesses.

RAYMOND McNELLEY.
